UNITED STATES PATENT OFFICE.

CHARLES W. ISBELL AND WILLIAM H. TAYLOR, OF NEW YORK, N. Y.

APPARATUS FOR GENERATING GAS.

SPECIFICATION forming part of Letters Patent No. 372,803, dated November 8, 1887.

Application filed June 30, 1886. Serial No. 206,678. (No model.)

To all whom it may concern:

Be it known that we, CHARLES W. ISBELL and WILLIAM H. TAYLOR, both of the city and county of New York, in the State of New York, 5 have invented a new and useful Improvement in Apparatus for Generating Gas, of which the following is a specification.

Our invention relates to apparatus for making what is commonly known as "water-gas," 10 which is generated by passing steam through a body of incandescent fuel, whereby the steam is decomposed, the hydrogen set free, and the oxygen combined with carbon to form carbonic oxide and carbonic acid, and by combining with the products of decomposition, either before or after their passage through incandescent fuel, and preferably after such passage, the vapor of naphtha or other liquid hydrocarbon. One form of generator for thus 15 making gas, and an example of which is shown in our Letters Patent No. 322,608, dated July 21, 1885, comprises a double generator, or two generating-chambers which are provided with grates and pipes for admitting air-blast for 20 blowing up the steam for decomposition, and which communicate near their top with each other, so that in generating gas the steam which is admitted below the grate in one chamber passes upward through the body of fuel 25 therein, and the products of complete or partial decomposition thence pass into the top of the next chamber and downward through the second body of fuel. The products of combustion in blowing up the generating-fires, preparatory to decomposing the steam and for the 30 purpose of raising such fires to a high point of incandescence, take the same course as the steam and products of decomposition in passing through the two generating-chambers. 35 When steam is admitted to the generating-chambers for decomposition, the fires become gradually cooled, and after a period—say one-half an hour, or thereabout—it becomes again necessary to blow up the fires with air-blast. 40 An important object of our invention is to provide a reservoir of heat between the two generating-chambers, wherein will be retained and stored up all surplus heat while blowing 45 up the generator, and which will give out such heat to the steam or products of decompositi- 50 on in their passage from one chamber to the other. By this feature of our invention

we enable decomposition to be carried on for a longer time after each time blowing up the generating-furnace, and we also insure a more 55 thorough and complete decomposition of the steam than has heretofore resulted from the operation of such apparatus.

This feature of our invention consists, essentially, in the combination, with a gas-generator comprising two chambers for containing fuel, which are provided, severally, with grates and with pipes for admitting air for blowing up and steam for decomposition, and with valved gas-outlets below the grates, of a superheater or superheating-chamber containing fire-brick or other refractory material arranged between the two generator-chambers and communicating with both said generator-chambers above the fuel in them, whereby the 60 products of combustion and decomposition in either chamber will be caused to pass from the upper part thereof through the superheating-chamber and into the upper part of the other generator-chamber. 65

The superheater included in the above combination may advantageously consist of two upright chambers, which communicate with each other at the bottom and with the generator-chambers at the top and above the fuel therein, whereby the products of combustion, while blowing up, and the carbonic acid and hydrogen, while decomposing steam, are caused 70 to pass downward and upward through said superheating-chambers in their course from 75 one generator-chamber to the other.

In our Letters Patent above referred to we employ a vaporizer which is arranged within a conduit through which pass both the products of combustion while blowing up and the gas which results from the decomposition of steam; and the quantity of naphtha-vapor which is produced while blowing up is stored within a supply-reservoir or storage-tank, from which it is supplied to aid in enriching the 80 great volume of gas which is produced when steam is first turned on after blowing up. According to that patent the products of combustion and the gas were always effective in 85 vaporizing the oil or naphtha, and no provision was afforded for controlling such vaporization in case it might be excessive.

A further object of our present invention is to enable the vaporizing of naphtha or other

hydrocarbon liquid to be secured under perfect control; and our invention consists in other novel combinations of parts, which include a vaporizer formed by transverse partitions in a conduit through which the products of combustion and the gas escape, and tubes connecting such partitions and forming around them a reservoir for hydrocarbon liquid and through them a passage for products of combustion and gas. Said combinations also include a by-pass pipe connecting the portions of the conduit on opposite sides of the vaporizer and valves whereby the passage of products of combustion and gas through the vaporizer and the by-pass may be controlled at the will of the operator. In case it is found that too much naphtha-vapor is being produced, the products of combustion or gas, as the case may be, are diverted from the vaporizer and passed through the by-pass, so that they are not effective in heating the vaporizer. We also provide the by-pass pipe with an external jacket, which may be filled with iron scrap or other material, and which may serve 25 as a superheater for the steam which is afterward admitted to the generator-chambers. In the accompanying drawings, Figure 1 is a sectional elevation of an apparatus embodying our invention. Fig. 2 is a rear elevation 30 thereof, portions of the gas-conduit, including the vaporizer and by-pass, being shown in section. Fig. 3 is a horizontal section of the apparatus. Fig. 4 is a vertical section of the vaporizer, which is arranged in the conduit 35 through which products of combustion and gas pass from the generator; and Fig. 5 is a sectional elevation of the by-pass portion of the conduit, with its steam-superheating jacket. Figs. 4 and 5 are upon a much larger scale 40 than the remaining figures.

Similar letters of reference designate corresponding parts in all the figures.

A A' designate the two generator-chambers of a double gas-generator, which are respectively provided with grates *b* and with pipes *b'*, which support the grates, and which are perforated for the free escape of air-blast for blowing up the chambers and of steam when employed for decomposition. At the top of 45 each chamber is a feeding-throat, *b*², which may be closed by a suitable cover, *b*³, and through which fuel is introduced in quantity as desired into the generator-chambers.

B designates a fixing furnace or chamber, 55 through which the gas is passed after the naphtha or other oil-vapor has been added to it, in order to properly fix the oil-vapor and convert it into a permanent gas. This fixing-chamber, also, is provided with a grate, *b*, supported by 60 perforated pipes *b'*, through which air-blast may enter below the grate for blowing up the fire in the fixing-furnace. This fixing furnace or chamber B also has at the top a feeding-throat, *b*², which is closed by a suitable cover, *b*³, and through which fuel may be introduced 65 into it in quantity as desired. The gas which

enters the top of the fixing-chamber, as we shall hereinafter describe, passes downward through the fire in the fixing-chamber and issues therefrom through a gas-conduit, *c*, into a wash-box, *C*, and from the wash-box escapes for storage or other purpose through a conduit, *C'*.

The air for blowing up is supplied from any suitable blower or apparatus through a supply-pipe, *b*⁶, and therefrom is conducted through distributing-pipes *b*⁵, in which are suitable valves, *b*⁴, to the perforated pipes *b'*, which are below the grate. These valves *b*⁴ and distributing-pipes *b*⁵ are arranged to supply the air-blast separately to either of the generator-chambers A A' or to the fixing-chamber B. The steam is supplied to the pipes *b'* of the generator-chambers A A' from a steam-supply pipe, *d*, through distributing-pipes *d'*, provided with suitable valves, and the steam to be employed may be taken from a boiler properly located and may be superheated in any suitable manner—for example, by a superheater, which we shall hereinafter describe.

Between the generator-chambers A A' are superheating-chambers D D', which are filled nearly to the top with fire-brick, tiles, or other suitable refractory material, and which communicate, respectively, by throats or passages *c* *c'*, with the two generator-chambers A A'. The material within the superheater-chambers D D' is supported by an arch, *D*', at the bottom, as shown in Fig. 1, and in which are perforations, so as to afford a free communication between the two chambers D D' at the bottom.

When air-blast is admitted below the grate of one chamber—the chamber A, for example—in order to blow up the fires, the blast and products of combustion pass upward through the fuel in the chamber A, thence through the throat *c*', and downward through the brick or refractory material in the chamber D, thence upward through the same material in the chamber D', and through the throat *c*' to the generator-chamber A', and thence downward through the fuel therein, making its escape below the grate of the chamber A'. When air-blast is admitted below the grate in the chamber A', the products of combustion take just the reverse course, and when steam is admitted to either of the generating-chambers it takes the same course 120 through the superheater-chambers D D' as described with reference to the air-blast and products of combustion. The consequence of this operation is that while blowing up either generator-chamber the refractory material 125 within the superheater-chambers D D' becomes heated to a very high degree, and when steam is first turned on to either chamber it receives a considerable increment of heat from the refractory material in the superheater-chambers D D', and hence is more thoroughly 130 decomposed. By the employment of these

chambers D D' we enable decomposition of steam to be carried on for a longer time without blowing up the furnace, and we also insure a more thorough and complete decomposition of the steam and the production of a better and more perfect quality of gas than has been possible without these superheater-chambers.

By the statement that the superheater chambers D D' are arranged between the generator-chambers A A' we do not mean that they are literally in the same vertical plane with and between these generator-chambers, but that they are so connected with the generator-chambers that products of combustion and steam or products of decomposition have to pass through them in order to travel from one generator-chamber to the other.

From below the grates of the two generator-chambers A A' lead the main outlets e e' for products of combustion and gas, and the course of the gas and products of combustion from each of the generator-chambers will be best understood from Fig. 2. The outlets e e' may 20 be closed by suitable covers, e'', as shown at the right hand of Fig. 2, and these outlets communicate, through suitable valves, e^3, in valve-boxes E' E, with a horizontal conduit portion, E^2, from which leads a vertical conduit portion, E^3. The vertical conduit portion E^3 is provided at the top with a purge-valve, e^4, and an escape-pipe, E^4, for the products of combustion, and from the conduit portion E^3, at a point below the valve e^4, a branch conduit portion, E^5, leads horizontally to the fixing-chamber B and communicates therewith near the top.

The valves e^3 in the valve-boxes E E' may be of soapstone or other material which will 40 not be injured by heat, and they may be operated by handles and connections e^6, as shown at the right hand of Fig. 2. While blowing up the chamber A, or while admitting steam thereto for decomposition, the valve in the box E leading therefrom will be closed and the valve in the box E' will be opened, while when blowing up the generator-chamber A' or admitting steam thereto the valve in the box E' will be closed and the valve in the box E will be opened. While blowing up either 50 chamber the valve in the box e^4 will be opened, so as to permit the products of combustion to escape freely through the pipe E^4, and while decomposing steam the valve in the box e^4 will be closed and the gas resulting from decomposition will pass through the branch or horizontal pipe E^5 to the fixing-chamber B.

The vaporizer which we prefer to employ is formed in the upright conduit E^3, near its 60 lower end, and consists of horizontal partitions f, extending across the conduit, and tubes f', connecting the partitions. The space around the tubes f' forms a reservoir for naphtha or other hydrocarbon liquid, which may be delivered thereto from a tank or reservoir, F, through a pipe, f^2, and the tubes themselves

afford a free passage for the products of combustion and gas, in order to vaporize the hydrocarbon liquid which surrounds the tubes. From this vaporizer the hydrocarbon vapor 70 passes through a pipe, f^3, to a storage-tank, F', and this pipe f^3 also communicates with the conduit E^3, immediately above the vaporizer and under control of the valve f^4.

While blowing up the generator-chambers 75 the valve f^4 is closed and the hydrocarbon vapor is stored within the tank or reservoir F'; but when steam is first turned on to the generator-chambers for decomposition the valve f^4 is opened, and the volume of vapor stored 80 within the tank F' is delivered to the conduit E^3 to mingle with the gas passing through the same.

In some cases the heat from the products of combustion and the escaping gas will vaporize 85 a greater quantity of hydrocarbon liquid than is desired, and in order to properly control the vaporization we provide a by-pass pipe, E^6, which extends upward from the horizontal conduit portion E^2, and communicates with 90 the upright conduit E^3 at a point above the vaporizer; and on the vaporizer f f', and also at the base of the by-pass pipe E^6, are valves h h', which are arranged within suitable slide-ways i, as shown in Figs. 4 and 5, and which 95 may be operated by suitable rods or stems, h^2. These valves may be of fire clay or other refractory material.

If while blowing up the generator-chambers it is found that the vaporization of hydrocarbon liquid is too rapid, the valve h', controlling the vaporizer, is closed, and the products of combustion and blast are caused to pass through the by-pass pipe E^6 around the vaporizer. When all the heat of the products of 105 combustion or of decomposition are to be availed of for vaporization of the liquid, the valve h, controlling the by-pass pipe E^6, is closed, and the valve h', controlling the passage through the tubes f' of the vaporizer, is 110 opened.

We have shown the by-pass E^6 as surrounded by an external jacket, j, which may be packed with scrap-iron or other loose heat-retaining material, j', and the steam which is to be employed for decomposition may be admitted to this jacket through a pipe, j^2, and may pass from the upper part of the jacket through the pipe d to the perforated pipes b' of the generator-chambers, to be therein decomposed, as 120 above described.

We are aware that it is not new to construct a generator with two fuel-chambers which are formed within a brick structure having super-heating-spaces within its walls and a super-heating-chamber between the generating-chambers, and that both air for blowing up and steam for decomposition have been passed through the superheating spaces and chamber before being admitted to the generating-chambers. The products of combustion or decomposition were in this apparatus not passed 125 130

through such superheating spaces and chamber, and we do not include such an apparatus in our invention.

We are also aware of United States Patent No. 269,162, granted December 12, 1882, to H. M. and J. S. Pierson, and do not claim an apparatus constructed as therein set forth. In that patent is shown an apparatus comprising fuel-chambers and an interposed chamber containing fire-brick or a refractory material; but the fuel-chambers do not have an arrangement of pipes whereby air may be admitted alternately to them for blowing them up, and the products of combustion passed through them alternately in opposite directions; nor do they have provision for admitting steam alternately to them. They are connected so that the products of combustion always pass through them in one direction for blowing up, and in decomposing steam the steam and products of decomposition always pass through them in a reverse direction. In that apparatus the superheating-chamber, to which the hydrocarbon is also admitted, is connected at its lower part with the lower part of one fuel-chamber and at its upper part with the upper part of the other fuel-chamber, and hence the fuel-chambers and the superheating-chamber are not arranged and connected for operation as shown and described by us.

Our invention is only intended to relate to apparatus having two generator-chambers for fuel, which are alternately blown up and alternately used for decomposition, and in which the air and steam or products of decomposition pass upward through one of said chambers and then downward through the other of said chambers in one or other direction, according to which chamber the air and steam are first admitted. After each blowing up the steam and products of decomposition take the same course as that which has been taken by the air.

We make no claim herein to the particular construction of vaporizer for hydrocarbon liquid.

We are aware that it is not new to pass the products of combustion from a furnace through a vaporizer or a separate smoke-pipe, at the will of the operator, and we are also aware that it is not new to superheat steam for the generation of gas by passing it through a jacket around a pipe through which gas passes. Therefore we claim none of these features, broadly, as of our invention, and only seek to claim such novel combinations of parts as are herein shown and described. In the operation of our apparatus it is advantageous to have the products of combustion and decomposition pass through the same pipe, as then both may be employed to heat the vaporizer; and the by-pass E^6 , connecting the conduit portions E^2 E^3 and the superheating-jacket j , provides for utilizing the products of combustion and products of decomposition, either or both, for heating either the superheater or vapor-

izer, as the conditions of operation may render most desirable.

What we claim as our invention, and desire to secure by Letters Patent, is—

1. The combination, with a gas-generator comprising two chambers for containing fuel and which are provided, severally, with grates and with pipes for admitting air-blast for blowing up and steam for decomposition, and with valved outlets below the grates, of the superheater or superheating-chamber containing fire-brick or other refractory material arranged between the two generator-chambers and communicating with both said generator-chambers above the fuel in them, whereby the products of combustion and decomposition in either chamber will be caused to pass from the upper part thereof through the superheating-chamber and into the upper part of the other generator-chamber, substantially as herein described.

2. The combination, with a gas-generator comprising two chambers, A A' , for containing fuel, and which are severally provided with grates and with pipes for supplying air-blast for blowing up and steam for decomposition, and with valved outlets below the grates, of a superheater arranged between the generator-chambers and composed of two upright chambers, D D' , containing fire-brick or other refractory material, said superheater-chambers being in communication with each other at the bottom and communicating at the top with the two generator-chambers above the fuel in them, whereby the products of combustion and decomposition in either generator-chamber will be caused to pass from the upper part of that chamber through the two superheating-chambers and into the upper part of the other generator-chamber above the fuel therein, substantially as herein described.

3. The combination, with a gas-generator comprising the two chambers A A' and the conduit E^2 E^3 , leading therefrom, and through which pass products of combustion while blowing up and gas while decomposing steam, of a vaporizer for hydrocarbon liquid in said conduit, a by-pass, E^6 , connecting the portion E^2 of the conduit, which is between the generator and vaporizer, with the portion E^3 of the conduit beyond the vaporizer, and valves whereby the passage through the vaporizer and by-pass may be controlled, substantially as herein described.

4. The combination, with a double gas-generator and a conduit leading therefrom and through which pass the products of combustion while blowing up and gas while decomposing steam, of a vaporizer for hydrocarbon liquid in said conduit, a by-pass connecting the portions of said conduit on opposite sides of the vaporizer and which is jacketed to form a superheater for steam, and valves whereby the passage through the vaporizer and by-pass may be controlled, substantially as herein described.

5. The combination, with a double gas-generator and the outlets therefrom for products of combustion and gas, and connected by the valve-boxes E E' and the cross-conduit portion E², of the upright conduit portion E³, containing a vaporizer, the by-pass E⁶, connecting the conduit portion E² with the portion E³ above the vaporizer, and valves h h' at the communica-

tion of the conduit portion E² with the conduit portion E³ and by-pass E⁶, substantially as herein described.
